UNITED STATES PATENT OFFICE.

JOHN T. NESDALL, OF BROOKLYN, NEW YORK.

STAIR STRUCTURE.

1,343,739.

Specification of Letters Patent. Patented June 15, 1920.

Application filed July 7, 1919. Serial No. 302,919.

To all whom it may concern:

Be it known that I, JOHN T. NESDALL, a citizen of the United States of America, residing at Brooklyn, in the county of Kings 5 and State of New York, have invented certain new and useful Improvements in Stair Structures, of which the following is a specification, reference being had therein to the accompanying drawing.

10 This invention relates broadly to stair structures and more specifically to that class in which the stair components or units are, in the main, constructed of pressed steel.

The object is to provide a stair-structure 15 in which there are, in one aspect of the invention, but two components, namely, a combined tread-and-riser member, and a stringer-member at each end of the combined member, each of the tread-and-riser 20 members being provided with coacting integral means for securing these members together and for attaching these members to the stringer-members.

Another object within the contemplation 25 of the invention is to provide a stair component, complete in itself, for attaching it to a corresponding stair component and for securing a plurality of these components to a stringer-component.

30 The invention, in another aspect, contemplates the provision of an integral tread-and-riser component, a pair of stringer-components, and means associated with the ends 35 of the tread-and-riser components for securing these components to the stringer-components.

Another object within the contemplation 40 of the invention is so to construct these comparatively few components that they are adapted to be conveniently and rapidly assembled and, withal, possess a high degree 45 of strength and rigidity.

The invention seeks in general to provide 45 a stair structure which is particularly well suited to meet the requirements of the rigid fire-regulations enforced in the large cities and yet, by reason of its type and construction, is adapted for use in residences, etc. From an operative standpoint, it will in 50 practical use possess a high degree of efficiency and durability and, from a structural standpoint, it is of great simplicity.

The various objects and advantages of the 55 structure will for the most part be obvious from the annexed drawings and will also be apparent from the following description.

The invention resides broadly in the features of construction, in the novel combination of elements, and in the co-operating ag- 60 groupment of such elements, all as will be exemplified in the construction hereinafter set forth, and the scope of application of which will be indicated in the claims hereto appended.

That the invention may be clearly com- 65 prehended, drawings illustrating some of the many possible utilizations of the same are appended hereto as a part of this disclosure; it being manifest that other possible utilizations and embodiments (employing the un- 70 derlying principles and salient features of my invention) fall within the spirit thereof and within the objects contemplated thereby.

In these drawings:

Figure 1 is a fragmentary view in perspective of a stair-structure built in accordance with one embodiment of my invention; 75

Fig. 2 is a view in perspective of one of the combined tread-and-riser members, complete and ready for assemblage; 80

Fig. 3 is a fragmentary view, in perspective, of one of the stringer-members or components;

Fig. 4 is a fragmentary view in perspec- 85 tive, a section of one of the stringer com- 85 ponents being broken away to show its integral, unit-supporting flange and, also, two of the associated stair-units;

Fig. 5 is a view in vertical longitudinal section, showing one of the stringer com- 90 90 ponents in elevation, and two of the stair-units in section, and illustrating, particu- 95 larly, the assembled relation of the flanges on the riser and tread of the components and the manner of attaching these to each other and to the stringer component;

Fig. 6 is a similar view of a modified form 100 of construction, this modification residing, primarily, in forming the unit-securing lug or element straight instead of bent or angu- 100 lated, as in the embodiment of Figs. 1 to 5; and

Figs. 7 and 8 are views in vertical longitudinal section and in perspective, respectively, of still another modified form of construction. 105

Referring to the drawings, it will be noted that the reference-character 1 designates a combined member or stair-unit including, as an integral structure, a tread or tread-portion 2, a riser or riser-portion 3, an elongated vertical flange 4 upstanding from the 110

tread-portion and an elongated horizontal flange 5 outstanding from the riser-portion. This combined member is preferably constructed of pressed steel and, in both embodiments herein disclosed, it is in the general form shown. In the embodiment of Figs. 1 to 5, it is one of the two primary components of the structure; while, in the embodiment of Figs. 7 and 8, it is one of the 10 three primary embodiments of the structure.

The second component of the structure includes, at opposite ends of the combined member, a side stringer or stringer-member 6. Preferably and as shown, each stringer 15 is provided with an inwardly-extending member-supporting portion or flange 7 of substantially the same length as the stringer itself.

At equi-distantly spaced points, the 20 stringer-flange 7 is provided with member-seating recesses or cutouts 8. In the preferred embodiment of my construction, the edges of the flange which form the walls of the cutouts are practically parallel to each 25 other and are cut at an angle to the plane of the surfaces of the flange.

Preferably and as shown, the flange 4 of the tread-portion is of a width less than that of the tread 2. The tread is provided or is 30 formed with pendant elements or pieces 9 which extend somewhat below the lower surface of the tread; and these elements 9 are adapted to project through the recesses 8 in the stringer flange.

35 The outstanding flange 5 on the riser 3 is of a width-wise dimension less than that of the riser and is adapted to occupy the position between the pendant pieces or elements 9 when two of the units are aggregated on the stringers. Thus, it will be seen that the flange 4 on the tread occupies a position in front of and parallel with the outer surface of the riser of the proximate unit when two units are assembled on the stringers; and, 45 likewise, each of the flanges 5 on each stair-unit underlies the lower surface of the riser. In consequence, each stair-unit rests upon and is supported directly by the flange 5 of its proximate stair-unit, while the pendant pieces 9 effect an interlocking of two units 50 with each other and to the stringers.

In the preferred construction of the invention, the pendant pieces 9 are bent or curved somewhat, as shown at 10 particularly in Figs. 4 and 5, so as to engage the corner of the recess 8 in the stringer flange and thereby effect a more complete and rigid interlocking of the units and stringer members.

In Fig. 6, the pendant elements or pieces 9 60 are, as a modification, shown straight.

In both of these forms of construction, no other securing means are employed for fastening the stair-units to each other and to the stringers.

65 In Figs. 7 and 8, however, I have shown

a modified construction, in which a unit-holding device is employed. In this instance, the stringer flange 11 is provided, at equi-distantly spaced points, with member-receiving recesses or cutouts 12, the edges 70 thereof being practically parallel to each other but cut at an angle to the plane of the surfaces of the flange. Juxtaposed to each recess is a bolt-hole adapted to receive a member holding an anchoring element which, in 75 this instance, is disclosed as a bolt 13 adapted to project through the hole, as shown. This member-holding element constitutes the third of the primary components of the structure of Figs. 7 and 8. 80

The assemblage.—Referring to the embodiment of Figs. 1 to 5, it will be seen that the stringers 6 having been set up, in much the usual manner, with their flanges extending toward each other, a combined member 1 is positioned so that its lower, flanged portion 5 is seated in one of the member-receiving recesses in each stringer. When thus disposed, the lower face of the flange 5 will rest on the edge or corner 14, while the rear surface of the riser-portion will engage the edge or corner 15. Then, another of the combined members 1 is similarly seated and, at the same time, the pendant-elements 9 are disposed at opposite ends of the flanged portion 4 and through the recesses 8 in the stringer flange 7 and under and in engagement with the edge or corner 16 of the stringer flange. When thus aggregated, each stair-unit is interlocked with two of the 100 proximate units and also with the stringers. 95

Referring to the embodiment of Figs. 7 and 8, it will be seen that, after the stair-units are assembled on the stringer flanges, as already described, the bolts 13 are 105 threaded into the stringers and made secure therein so as to fasten the stair-units to the stringers and thus indirectly fasten the stair-units to each other.

In these different embodiments, the structure thus constituted of the two components—the stair-unit and the stringer-member—would provide a substantial and efficient stair structure, since one combined member (by reason of its co-acting relation 115 to the one next above it) would serve to maintain that which is next above it in position.

It will now be perceived from the foregoing that I have succeeded in devising a stair-structure which is well adapted to achieve the several objects and advantages in view. It is simple and compact in form, and the components of which it is constituted are inexpensive to manufacture and very readily 120 fabricated.

As many modifications and variations can be obviously made in this construction without departing from the spirit thereof or sacrificing any of the salient features or under- 125 130

lying principles of the same, it is intended that all matter contained in the foregoing description and shown in the accompanying drawings shall be interpreted as illustrative 5 and not in any limiting sense.

What I claim is:—

1. A metallic stair including a pair of side stringers having inwardly-extending unit-sustaining sections, and a plurality of 10 associated stair-units securable thereon and comprising, each, a tread-portion and an integral riser-portion, each of these portions being provided with an elongated angular flange of unbroken continuity but of less dimension in one direction than the longitudinal dimensions of either the tread or the 15 riser-portions, the flange of the tread-portion upstanding therefrom and occupying a position in front of and in engagement with the front face of the proximate riser-portion, and the flange on the riser-portion extending at approximately a right angle therefrom and underlying a section of the tread-portion and also the flange upstanding 20 therefrom.
2. A metallic stair including a pair of side stringers having inwardly-extending unit-supporting flanges provided with unit-receiving recesses; a series of stair units 25 associated therewith and comprising, each, a tread-portion and an integral riser-portion, each of these portions being provided with an elongated angular flange, the flange of the tread-portion upstanding therefrom and occupying a position in front of and in parallelism with the riser-portion of the proximate unit, and the flange on the tread-portion underlying the underside of the riser-portion, the tread-portion being formed 30 with a plurality of pendant integral lugs at its opposite extremities and extending in a direction opposite to its upstanding flange, said lugs engaging opposite ends of the flange on the riser-portion and extending 35 through the recesses in the stringer flanges.

3. A metallic stair including a pair of side stringers having inwardly-extending unit-sustaining flanges provided with spaced apart cutouts or recesses; and a series of 40 stair units mounted thereon and comprising, each, a tread-portion and an integral riser-portion, each of these portions being provided with an elongated angular flange, the flange of the tread-portion upstanding 45 therefrom and formed at an approximately right angle to the upper surface thereof and occupying a position in front of and in parallelism with the proximate riser-portion, and the flange on the riser-portion extending 50 at approximate right angles to the vertical surface of the riser portion and underlying and supporting the flange-provided section of the tread-portion, and means for securing units to each other and to the 55 stringers including integral, pendant ele-

ments formed at the opposite extremities of the tread-portion and extending below the flange on the riser-portion and through the cutouts in the stringer-flanges, the pendant elements and the upstanding flange on the 70 tread portion extending in opposite directions and being disposed in substantially vertical alinement.

4. A metallic stair including a pair of side stringers having inwardly-extending unit-sustaining flanges provided with spaced apart cutouts or recesses; and a series of 75 stair units mounted thereon and comprising, each, a tread-portion and an integral riser-portion, each of these portions being provided with an elongated angular flange, the flange of the tread-portion occupying a position in front of and in parallelism with the proximate riser-portion, and the flange on the 80 riser-portion underlying and supporting the flange-provided section of the tread-portion, and means for securing units to each other and to the stringers including integral, pendant elements on the tread-portion and extending below the flange on the riser-portion and through the cutouts in the stringer-flanges and disposed in substantially the 85 same vertical plane as, and in alinement with, the upstanding flange on the tread portion, said elements being angulated to engage the under face of the stringer-flanges.

5. A metallic stair including a series of associated stair units comprising, each, a tread-portion having an upstanding, right angular flange of less width than that of the 90 tread-portion, the latter being provided at its extremities with pendant unit-attaching elements integral with the tread-portion, and a riser-portion formed with an outstanding, right angular flange of unbroken continuity 95 and of a width less than that of the riser-portion.

6. A metallic stair including a series of associated stair units comprising, each, a tread-portion having an upstanding, right 100 angular flange of less width than that of the tread-portion, the latter being provided with pendant unit-attaching elements integral with the tread-portion, and a riser-portion formed with an outstanding, right angular flange of a width less than that of the 105 riser-portion, the pendant elements on the tread-portion occupying a position at opposite ends of the flange on the riser-portion and extending downwardly away from the 110 flange on the tread portion.

7. A metallic stair including a series of associated stair units comprising, each, a tread-portion having an upstanding, right angular flange of less width than that of the 115 tread-portion, the latter being provided with pendant unit-attaching elements integral with the tread-portion, and a riser-portion formed with an outstanding, right angular flange of a width less than that of the 120 125 flange on the tread portion.

- the riser-portion, the pendant elements on the tread-portion extending downwardly and disposed in the same vertical plane as the upstanding flange on the tread portion 5 and also occupying a position at opposite ends of the flange on the riser-portion, said elements being angular with respect to the under surface of the flange on the riser-portion to perform a holding action.
- 10 8. A metallic stair including a plurality of associated stair-units, each unit comprising a tread-portion having a right-angular upstanding flange of a width less than that of the tread-portion and also having 15 two unit securing, integral elements depending at substantially right angles to and below the lower face of the tread-portions, and the riser-portion having also a right-angular flange of a width less than that of the tread-portion, the depending elements 20 occupying, when two units are in operative association, a position at opposite ends of the flange on the riser-portion extending in the same general vertical plane as the flange 25 on the tread portion but in an opposite direction therefrom.
9. A metallic stair-structure including a plurality of self-securing stair-units, each comprising a tread-portion formed with an 30 integral, upstanding flange of unbroken continuity and with two unit-securing elements spaced apart from each other by the upstanding flange and depending from the tread-portion, and a riser-portion formed 35 with an integral flange of a width less than that of the riser-portion and adapted to occupy a position between the depending elements, the latter being disposed in parallelism with the riser portion but spaced 40 therefrom by the tread portion and being bent to perform a securing action when two units are mounted, one upon the other.
10. A metallic stair-unit comprising a 45 tread formed with an integral, upstanding right-angular flange of a width less than that of the tread-portion, and with pendant

unit-securing elements, and a riser formed with an angulated flange of a width less than that of the riser-portion, said unit-securing elements being spaced apart from 50 each other a distance equal to the width of the flange on the tread portion.

11. A metallic stair unit comprising a tread-portion formed with an integral, upstanding right-angular flange of unbroken 55 continuity and of a width less than that of the tread portion, the tread portion being also formed at its extremities with two pendant unit-securing lugs extending from the tread portion in a direction opposite that 60 of the flange thereon, and a riser portion formed with a right-angular flange of approximately the same width as the flange on the tread portion.

12. A metallic stair including a plurality 65 of associated stair units, each unit comprising a tread portion formed with an integral, upstanding right-angular flange of unbroken continuity and of a width less than that of the tread portion, the latter being 70 also formed with two pendant unit-securing elements spaced apart from each other a distance equal to the width of the flange on the tread portion, and a riser-portion formed with a right-angular flange 75 of approximately the same width as that on the tread portion, in combination with a pair of stringers formed with spaced apart recesses in which said lugs are seated; the flange on the riser portion underlying and 80 supporting the tread portion, and the flange on the tread portion being disposed in front of the front surface of the riser portion and occupying a position at right angles to the underlying flange on the riser portion. 85

In testimony whereof I affix my signature in presence of two witnesses.

JOHN T. NESDALL.
